UNITED STATES PATENT OFFICE.

PARKER H. MCKEE, OF WOODBURY, NEW JERSEY, ASSIGNOR TO BERGER BROS. COMPANY, OF PHILADELPHIA, PENNSYLVANIA, A CORPORATION OF PENNSYLVANIA.

DESIGN FOR A CONDUCTOR PIPE STRAP END.

Application filed February 9, 1925. Serial No. 12,312. Term of patent 14 years.

To all whom it may concern:

Be it known that I, PARKER H. MCKEE, a citizen of the United States, residing in Woodbury, county of Gloucester, State of New Jersey, have invented a new, original, and ornamental Design for Conductor Pipe Strap End, of which the following is a specification, reference being had to the accompanying drawing, which forms a part thereof.

Fig. 2 is a perspective view of the subject of Figure 1.

I claim—

The ornamental design for a conductor pipe strap end, as shown.

In testimony of which invention, I have hereunto set my hand, at Philadelphia, on this 5th day of February, A. D. 1925.

PARKER H. MCKEE.
